UNITED STATES PATENT OFFICE.

CHARLES W. HOTTMANN, OF PHILADELPHIA, PENNSYLVANIA, ASSIGNEE OF ONE-HALF TO AUGUST H. E. JUERGENS, OF PHILADELPHIA, PENNSYLVANIA.

SAUSAGE-STUFFER.

1,133,030.

Specification of Letters Patent. Patented Mar. 23, 1915.

Application filed February 26, 1914. Serial No. 821,118.

To all whom it may concern:

Be it known that I, CHARLES W. HOTTMANN, a citizen of the United States, residing in the city and county of Philadelphia, State of Pennsylvania, have invented a new and useful Sausage-Stuffer, of which the following is a specification.

My present invention consists of a novel sausage stuffer, wherein novel means are provided for causing the sausage or other material to pass into a skin, bag or other receptacle, under any desired or predetermined pressure.

It further consists of a novel sausage stuffer, in which novel means are employed to effect the discharge of the material from the machine.

It further consists of a novel construction of feed blades, and novel means for automatically cleaning the same during the operation of the machine.

It further consists of a novel manner of causing, at predetermined times, a partial rotation of said feed blades.

It further consists of a novel construction of a shoe or slide, and a novel construction of tracks coöperating therewith.

It further consists of a novel construction and arrangement of a tension device, and a valve controlled thereby.

It further consists of a novel construction of a casing and coöperating parts, and other novel features of construction, all as will be hereinafter specifically set forth.

For the purpose of illustrating my invention, I have shown herein a preferred embodiment thereof, which in practice will give satisfactory and reliable results, although it is of course to be understood that the various instrumentalities of which my invention consists can be variously arranged and organized, and that my invention is not limited to the exact arrangement and organization of these instrumentalities, as herein set forth.

Figure 1 represents a side elevation of a sausage stuffer embodying my invention. Fig. 2 represents a plan view thereof. Fig. 3 represents a plan view of the casing having certain of the operating parts removed.

Fig. 4 represents a plan view of a cover plate and cam supporting members. Fig. 5 represents, on an enlarged scale, a sec-

tional elevation of a portion of my device, the section being taken on line $x-x$, Fig. 55 2. Fig. 6 represents a plan view, showing a portion of my device. Fig. 7 represents a section on line $y-y$ of Fig. 6. Fig. 8 represents in perspective one of the shoes or slides employed. 60

Similar numerals of reference indicate corresponding parts in the figures.

Referring to the drawings: 1 designates standards or a supporting framework, constructed in any desired manner, and in 65 which is journaled a main driving shaft 2, which is driven by any desired source of power, or manually, if desired, and for purposes of illustration I have shown said shaft 2 as being provided with the pulleys 70 3, whereby the latter are adapted to receive a belt and to be driven by any desired source of power. The driving shaft 2 has secured thereon a gear 4, which meshes with a gear 5, fixed on a shaft 6, 75 which latter is journaled in the machine frame, and said gear 4 also meshes with a gear 7, which is fixed on a sleeve 8, by means of a set screw 9, said sleeve 8 being loosely mounted on the shaft 6. The 80 sleeve 8 is journaled in the bottom casing member 10, which latter has removably connected therewith, an upper casing member 11, the upper portion of which forms a hopper 12. The bottom casing member 10, 85 as best seen in Figs. 3, 6 and 7, is provided with a track 13, one end of which is beveled or inclined, as indicated at 14, at which point the annular track 13 is cut away or interrupted, as will be clearly understood 90 by reference to Fig. 3.

15 designates a second track, the ends of which are inclined or beveled, as indicated at 16 and 17, respectively. The bottom casing member 10, is also preferably provided with an annular groove 18, which is adapted to receive the bottom rib 19, of a ring or annulus 20, which latter is provided with an annular top rib 21, which is adapted to be seated in an annular groove 100 22, of a cover plate 23, which latter is secured to the casing member 10 by means of fastening devices 24. The cover plate 23 is provided with a central portion 25, and is cut away as indicated at 26 and 27, 105 in order to permit the material to pass

downwardly into the channel 28, formed between said plate 23 and the annulus 20, and the bottom casing member 10. This plate 23 is provided, on its under face, with 5 an annular track 29 and an inner curved track 30, the end of which preferably forms a straight wall. The track 30 is in vertical alinement with the track 15 carried by the bottom casing member 10, as will be understood by reference to Fig. 7.

32 designates the feed blades or paddles which are adapted to travel in the channel 28, and between the side of the casing member 10 and the annulus 20, and the top and 15 bottom portions of said paddle are preferably rounded, as will be best understood by reference to Fig. 5, and Fig. 6. Each feed blade or paddle 32 is provided with a stem 33, which passes through the annulus 20, 20 and has its inner end journaled in a hub 34, which is fixed to the sleeve 8, by means of a key 35, whereby said hub and said sleeve rotate in unison. For convenience of illustration, I have shown the annulus 20 as provided with apertures 36 through which said stems 33 extend, but it is within the scope of my invention to form the annulus 20 in separate parts instead of in one part.

37 designates a shoe which is apertured as 30 at 38, in order to permit a stem 33 to pass therethrough, said shoe being fixed to its respective stem, in the present instance, by means of a pin 39, although if desired this shoe may be cast integral with the stem 33 35 and its blade 32. Each shoe 37 is provided with an upwardly extending portion 40, preferably having a rectangular contour, and said shoe is also provided with a laterally projecting portion 41, which is also preferably of a rectangular contour. The lug or projection 41 of a shoe, travels between the tracks 13 and 29, while the lug 40 co-operates with the tracks 15 and 30.

42 designates a delivery spout having lugs 45 43, which are adapted to interlock with the groove 44 of a spout 45 which is preferably provided with a conical end, thereby adapting the same to be received in a skin or casing which is to be filled.

50 46 designates an actuating handle for locking the spout in assembled position. By such construction spouts of different sizes may be readily removed or connected with respect to the discharge opening from the machine.

47 designates a block secured to the bottom casing member 10, by means of fastening devices 48, of any desired type, said block having a curved side face 49, the forward end of which is in alinement with the wall of the discharge spout 42. The upper wall of said block 47 is preferably substantially flat as indicated at 50, so that when a feed blade 32 is passing thereover, it will pass in close proximity to said upper

wall 50, which latter will serve as a cleaning means for one side of said blade.

51 designates a valve member, the lower end of which normally abuts against the side wall of said block 47, said valve member 51 being carried by a rod 52, journaled in the casing member 10 and the annulus 20. This rod or shaft 52 extends exteriorly of the casing and is internally threaded in order to receive a manually adjustable screw 53, on which latter is provided the pins 54, which position a collar 55 so that the latter is prevented from relative longitudinal movement with respect to the screw 53.

56 designates a spring, one end of which is connected with a collar 55, while the other end thereof is connected to a fixed point, such as for example the pin 57. The adjusting screw 53 and the spring 56, and their adjuncts, form an adjustable tension device for the valve member 51, and thereby regulate the pressure under which the material passes through the delivery spout 45 into the skin or casing which is being filled.

As best seen in Fig. 7 the plate 23 is provided with a hub 58, having a key 59 (see Fig. 6), which latter interlocks with a recess in the hub 60, to which latter is secured 95 a stirring or agitator blade 61, and in the present instance these blades are integral therewith, and tend to feed the material downwardly into the feed channel. The annulus 20 is connected with the hub 34 100 by means of the arms or spokes 62.

The operation of my novel sausage stuffer will now be readily apparent to those skilled in this art, and is as follows: The sausage or other material which is to be packed into 105 the skin or casing, is placed in the hopper 12 and the driving shaft 2 is actuated in any desired manner, and owing to the construction and arrangement of the gears 4, 5, and 7, the mixing or agitating blade 61 110 will be revolved in one direction, while the feed blades 32 will be revolved in a reverse direction. The material feeds down between the blades 32, as will be understood by reference to Fig. 2, so that the material 115 is fed through the channel 28, beneath the plate 23. A slide or shoe 37, has one of its operative faces, such as for example the lug or extension 41, positioned to travel between the tracks 13 and 29, which will cause the feed blades 32 to assume a vertical position

120 during their revolution, but as soon as the lug 41 reaches the beveled or inclined end 14 of the track 13, the lug 40 passes up the incline space 16 on to the track 15, thereby 125 bringing a feed blade at such time into a substantially horizontal position. The material, such as for example the sausage, passes out the stationary discharge spout or opening 42, and through the removable dis-

charge spout or opening 45, and into the skin or casing, which is to receive the sausage. This action is caused by the curved face of the block 47, so that the sausage or other material is guided into said opening 42. It will be noted that the top wall or face of the block 47, is at such a height that when a feed blade is passing thereover in a horizontal position it will travel in close proximity to such wall, so that one face of the blade will be freed of any sausage or other material adhering thereto. On the further advancement of the feed blade it engages the valve or door 51, causing the same to open against the tension of the spring 56, and since the lower edge of said valve or door 51 is in contact with the upper face of the feed blade 32 passing thereunder, any sausage or material adhering to such face will be removed therefrom.

Special attention is directed to the manner in which I am enabled to pack the material in the skins or casings under any desired pressure, since the adjusting screw 53 may be regulated to vary the tension of the spring 56, so that at any predetermined pressure, the valve or door 51 will move toward its open position and permit the sausage or other material to pass therethrough, instead of forcing the same through the discharge opening 42. By such construction, I provide a safety or relief valve which prevents the material becoming packed too tightly in the skins or casings, and which prevents the bursting open of the skins or casings during the filling operation, since, as is well known some skins or casings will stand a much greater pressure than others. As the lug or extension 40 of a shoe 37, passes down the inclined end wall 17 of the track 15, the lug or extension 41 of said shoe will again engage with and be guided by the tracks 13 and 29, as is apparent.

It will be understood that the annulus 20 rotates in unison with the feed blades, and if desired the upper and lower ribs thereon, 18 and 21 respectively, and their coöperating recesses or grooves may be dispensed with, since their only function is to form a better fit between the bottom of the casing 10 and the top or cover plate 23, so that there is less likelihood of the material passing between said annulus and said casing 10 and said plate 23.

It will now be evident that in accordance with my present invention, I provide feeding or conveyer members which during a portion of their revolution travel in an upright position, and which when they arrive in proximity to the discharge opening, are automatically partially rotated, in conjunction with novel means for regulating the pressure on the material, so that such material may be passed into a container of any desired type, at a desired pressure, and I

also provide novel means for removing from a feed blade any material which adheres thereto.

In so far as I am aware, I am the first in the art to employ the above noted novel features, and it is to be understood that my claims thereto are to be interpreted with corresponding scope.

It will now be apparent that I have devised a novel and useful construction of a sausage stuffer which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a device of the character stated, a casing having a discharge port therefrom, feed blades mounted to revolve within said casing, means to impart a partial rotation to said blades during their travel, and means to revolve said blades.

2. In a device of the character stated, a casing having a discharge port therefrom, devices within said casing to form a feed channel communicating with said discharge port, feed blades mounted to pass through said channel, means to impart a partial rotation to said feed blades during their travel, and means to revolve said feed blades.

3. In a device of the character stated, a casing having a discharge port, a plurality of feed blades rotatably mounted within said casing, means to simultaneously rotate said feed blades, and means to cause said feed blades to travel at predetermined periods in a substantially upright position, and during other periods, in a path at an angle to their upright position.

4. In a device of the character stated, a casing having a discharge port, devices to form a feed channel communicating with said discharge port, said devices including a valve in said channel located beyond said discharge port to vary the pressure under which the material passes through said discharge port by permitting a portion of said material to return to said feed channel, and means to feed the material in said casing through said channel and said discharge port.

5. In a device of the character stated, a casing having a discharge port, means to feed the material in said casing to said discharge port, and devices including a valve located beyond said discharge port to cause

said material to pass through said discharge port, under a predetermined pressure by permitting a portion of said material to feed into said casing beyond said discharge port.

6. In a device of the character stated, a casing having a discharge port, an annulus within said casing forming a feed channel, feed blades mounted in said annulus, a cover 10 for a portion of said channel, means to rotate said feed blades, shoes carried by said feed blades, and means common to said cover and said casing, and coöperating with said shoes to vary the position of said feed blades during their rotation.

7. In a device of the character stated, a casing having a discharge port, devices to form an annular channel communicating with said discharge port, a spring actuated 20 valve forming a closure for said channel at a point posterior to said discharge port, whereby when said valve is open, the material will be returned to said channel, and means to feed the material within said casing 25 into said channel.

8. In a device of the character stated, a casing having a discharge port, an annulus within said casing forming a feed channel, a plate covering a portion of said annulus, a block 30 in said channel in proximity to said discharge port and partially filling said channel, a valve closing the forward end of said channel, a feed blade, means to move said feed blade through said channel, and means to turn said blade to permit it to 35 pass between said valve and said block.

9. In a device of the character stated, a casing having a discharge port, means within said casing to form a feed channel in 40 communication with said discharge port, a

valve forming a closure for the forward end of said channel and when open permitting the return of material to said feed channel, a tension device for said valve, means to adjust said tension device, and means to feed 45 material into said channel.

10. In a device of the character stated, a casing having a discharge port, devices forming a channel in communication with said discharge port, a spring pressed valve 50 closing the forward end of said channel, a plurality of tracks common to said devices and said casing, a feed blade mounted to travel through said channel, means to cause such travel of said feed blade, and a shoe 55 carried by said feed blade and having operative faces coöperating with said tracks to periodically turn said blade toward a horizontal plane.

11. In a device of the character stated, a 60 casing having a plate spaced from its bottom forming an annular feed channel, and said plate being provided with an opening communicating with said feed channel, said casing having a discharge port communicat- 65 ing with said channel, means in proximity to said discharge port to direct the material thereinto, a valve pivotally mounted and having its lower end normally engaging said means to close said channel at one point 70 and when open permitting the material to return to said feed channel, a feed blade mounted to travel in said channel, means to revolve said blade, and means to automatically impart a partial rotation to said blade 75 during its revolution.
